COIN CHUTE

William Patzer and Walter A. Tratsch,
Chicago, Ill.

Application May 26, 1939, Serial No. 275,879

6 Claims. (Cl. 194—97)

This invention relates to coin testing devices and has as its principal object the provision of automatic blocking or deflecting means arranged for cooperation with a hand-operated discharge or scavenging gate in a gravity type coin chute.

A further and more particular object is the provision of blocking or deflecting means in a coin chute having a descending coin passage and a side exit which is normally closed by a gate, the deflecting means including a resilient member attached to a side wall of the chute opposite the exit opening and having a plurality of fingers projecting through the wall into the chute passage so that one of the fingers may engage the gate in its closed condition, to move the resilient member and withdraw another of the fingers from the passage and out of obstructing position in the latter to permit free passage of coins therein, the resilient member moving to project a withdrawn finger relative to the passage as soon as the gate begins opening movement.

Viewed from another aspect, it is an object of the invention to provide fraud preventive means for cooperation with the scavenging gate of a coin chute, said means including a spring strap attached at one end to the side wall of the chute and having a pair of fingers projecting through the wall into the chute passage, one of the fingers engaging the gate and the other finger projecting into a blocking position in the passage when the gate is opened to permit the strap to flex into its normal position.

Other objects, advantages and economies peculiar to the invention reside in certain details of construction, as well as the arrangement and operation of the parts described hereinafter as constituting the preferred embodiment of the invention, all of which will be more readily understood by reference to the annexed drawings, in which:

Fig. 1 is a side elevation of the coin chute, looking toward the scavenging gate, a portion of the latter being broken away to expose part of the fraud preventive means;

Fig. 2 is a fragmentary perspective showing the wall opposite the gate and the novel fraud-preventive means;

Fig. 3 is a fragmentary cross section looking in the direction of line 3—3 of Fig. 2;

Fig. 4 is a vertical sectional detail view of the coin chute as seen from line 4—4 in Fig. 1; and

Fig. 5 is a vertical sectional view, partly in elevation, showing the interior coin passage of the coin chute, and is taken substantially along line 5—5 in Fig. 4.

The coin chute is of the gravity type such as the one shown in our U. S. Patent No. 2,249,225 of July 15, 1941, and is preferably constructed with a pair of vertical wall plates mounted in spaced relation to define a vertical well or passage of considerable depth. At the upper end of the chute, there is provided a widened coin entrance 10 and beneath this entrance interiorly of the chute is a downwardly inclined ledge 11 (Figs. 1 and 5) terminating at an end 12 from which the gravitating coins depart into an enlarged part of the passage for movement into engagement with selecting means such as the deflector 13 or a rebound anvil 14 for ultimate guidance into an acceptance passage 15 or a reject passage 16. The latter passages are defined by a separator 17 having a deflecting point 18 on its side toward the anvil and an upper edge portion 19 which inclines away from the point 18 toward the acceptance opening 15.

The type of chute illustrated is adapted to accept coins of three denominations, for example, five, ten and twenty-five cent pieces. The arrangement is such that the ten and twenty-five cent pieces, by virtue of their mass and metallic content and the selective effect of a permanent magnet 20 having its poles positioned near the end 12 of the runway ledge, are caused to drop onto the deflector 13 for movement toward the left into the acceptance opening 15 either directly or by suitable angular contact with the surface 19 of the lowermost separator 17. The five cent pieces, however, depart from the end of the runway with greater energy and are carried down onto the anvil 14 to rebound from the latter over the selector or segregator 17 and into the acceptance passage. The normal operation of the coin testing chute being as shown and described in our aforementioned Patent No. 2,249,225.

The permanent magnet 20 is arranged with its pole pieces flush with the interior face of the wall upon which it is mounted at a point adjacent the terminating end 12 of the inclined ledge 11. A gate member 21 is hung on a pintle rod 22 seated in ears 23 along the top edge of the chute so that the gate pivots about a horizontal axis extending parallel with the width of the chute body. This gate member 21 forms a normal wall portion of the testing chute passage and is adapted to be swung about the pintle 22 by means hereinafter to be set forth. A plate 20' is fixedly attached to the gate member 21 and this plate 20' is of a size substantially corresponding to the exposure of the faces of the

two pole pieces which face into the coin passage as heretofore set forth. The plate 20' is of a paramagnetic metal and functions to confine the magnetic field set up between the two pole pieces to the area adjacent the terminating end 12 of the ledge 11.

The selective movement of the coins is determined in the first instance by their electrical conductivity. Dimes and quarters contain amounts of silver rendering them much more highly conductive in terms of ohmic resistance than is the nickel, it being known of course that nickel itself has a relatively high resistance constant. All coins in passing through the magnetic field of the permanent magnet encounter physical resistance in proportion inversely to their conductivity for a given strength of the field. The reason for this is that eddy currents are set up in the coin as the result of this movement through the magnetic field and these currents always produce their own field about the coin, which field is in opposition to the field which induces the eddy currents. In consequence of this, all coins lose kinetic energy in passing through the field of the stationary magnet, and since the dimes and quarters have less resistance, or in other terms a greater conductivity, the eddy currents induced therein will have a higher current value and therefore exert a stronger reactive field to oppose the movement of the coin through the main field. Conversely, the five-cent pieces having a higher resistance, resist the induction therein of eddy currents to a greater degree, and therefore the reactive field set up therein is weaker, in consequence of which the nickels are able to continue moving through the main magnetic field at a greater rate than is possible for the dimes and quarters.

The five-cent pieces therefore travel farther from the end 12 of the run-way ledge 11 and are able to strike the anvil 14. The quarter is slowed down considerably and therefore strikes the deflector 13 as does the dime, for the same reason. The selective action of the magnetic field is even more critical for silver-containing coins than for some others, and the dimes and quarters are very accurately guided on to the deflector 13, the gravity component having a critical effect also.

Associated with the coin chute herein described is a deflector member 35 which forms the subject matter of our Patent Serial No. 2,249,225, the application of which was copending with the present one. This deflector is fixedly mounted on the gate member 21 and has a lateral extension 36 projecting through an opening 37 formed in the gate member to provide a deflector means whereby coins or slugs having a lesser resistance or greater conductivity than dimes or quarters will be prevented from swinging about the terminal end 12 of the ledge 11 in a manner such that they will drop to the left of the testing ledge or testing deflector 13. The action of such coins is best illustrated in the dotted line showing in Fig. 5 wherein a coin having the characteristics of greater conductivity than acceptable coins is shown engaging the ledge 36 prior to being deflected to the dotted line trajectory.

In order to clear the chute of coin elements arrested by the magnet 20, or by any other testing means arranged to test coins in the region of the runway ledge 11 (e. g. feelers and the like), one side of the passage is cut away in the region adjoining and opposite the magnet 20 to provide a discharge exit, and this exit is normally closed

by the gate 21 which is hung on the pintle rod 22. This gate 21 forms a movable side wall of the shape shown in Fig. 1 to coact with the back wall of the chute to define a coin passage in the upper region of the chute. The lower region of the chute has a fixed wall F which with the back wall defines a coin passage adjacent the acceptance opening 15 and reject passage 16 (see Fig. 1).

Mechanism is provided for scavenging the device and this mechanism includes a lever 24 pivoted as at 25 on a side of the chute and having an extension 26 which passes through the chute to engage a roller 27 on the gate. By exerting a downward pressure on the handle portion 28 of the lever 24, the extension 26 will engage the roller 27 and the gate 21 will be swung outwardly into the dotted line position shown in Figs. 3 and 4. Simultaneously a roller 46 on the lever 24 will engage a cam 47 on a lever 29 pivotally mounted as at 38 on the back wall of the chute, and arrested coin elements will be dislodged by simultaneous downward movement of the sweep lever 29, so that the arrested coin elements will gravitate toward the reject passage 16 in the chute. Any coins or objects lodged on the runway ledge 11 above an arrested coin will gravitate onto a pitched pan P beneath the entrance opening 10 and be directed through the sidewise opening into a reject chute R.

Ordinarily, when an arrested coin element is dislodged from arrested position by the movement of the sweep 29, such dislodged coins gravitate at random along no particular trajectory and occasionally might fall in a direction toward the left of the deflector 13 and accidentally into the acceptance opening 15. Also by fraudulent operation of the scavenging lever 24, arrested coins may skillfully be manipulated toward the acceptance opening 15.

In order to prevent fraudulent manipulation of the gate to cause arrested coin elements to be worked into a position for continued movement down the passage, instead of being ejected, there is provided a fraud-preventive means in the preferred form of a spring strap 30 (Fig. 2) which has one of its ends anchored to the outer side wall of the chute opposite the gate by means such as the rivets 31. The strap is inclined downwardly from its anchorage in a general direction toward the anvil, and there is provided a pair of rigid fingers 32 and 33 projecting laterally of the strap into the chute passage through suitable openings in the chute body.

One of the pins 32 projects across the passage just beneath the lower end 12 of the coin ledge or rollway so as to be in an unobstructing position, and this pin (Fig. 3) is of a length adequate to cause its nose to bear against the inner side of the gate 21 when the latter is in its normally closed position, the length of this finger or pin 32 being such that when the gate is closed, the strap 30 will be flexed away from the chute into the position seen in Figs. 3 and 4, to withdraw the other finger 33 from obstructing position across the coin passage, the pin 33 being shorter than the pin 32. The disposition of the lower pin or finger 33 is such that it can block the coin passage area between the end 12 of the rollway and the deflector 13, and hence can block direct entrance into the acceptance passage 15 when the gate is opened.

As a result of the blocking effect of the finger 33, all arrested coin elements and all coins of the ten and twenty-five cent denomination

whether legitimate or not, will be caused to move toward the reject passage 16, and since the selective operation of the anvil is dependent upon the momentum of the coin, if it be a proper one, all arrested coin elements (and such coins as bound from the deflector 13) striking the anvil will move into the reject passage 16. Should scavenged coins escape the action of the sweep 28 by fraudulent manipulation of the gate and control mechanism in an effort to work the coins past the sidewise exit opening by rapid partial opening movements of the gate or by piling a series of coins up in the passage between the entrance 18 and the end 12 of the runway, or by other defrauding expediences. The finger 33 will be disposed across the coin passage and hence any coin falling in the direction of the acceptance opening 15 will be guided by the finger 33 as well as the deflector 13 toward the reject passage 16.

The fraud-preventing means may be made extremely sensitive by properly regulating the length of the strap 30, the lengths of the fingers 32 and 33 relative to each other and relative to the width of the coin passage, as well as the spacing of the fingers relative to each other, the 25 inclination of the passage and their respective distances from the anchored end of the strap 30. It will be apparent that the displacement of these fingers responsive to movement of the gate, is dependent, in part, upon the length of 30 the lever arm or strap 30 and the distance between the fingers relative to the flexing point or fulcrum of the strap or lever arm.

The objects and advantages of the invention may be realized in forms of construction other than that specifically described herein for purposes of illustration, and the foregoing description is not intended to be a limitation upon the invention except as may be provided in the appended claims.

Having thus described our invention, what we claim as new and desire to protect by Letters Patent is:

1. In a coin chute of the type having a descending coin passage with a sidewise exit opening and a normally closed scavenging gate for said opening, a plurality of exit passages below the level of said gate, and testing means for variously directing coins into said exit passages; fraud-preventive means comprising: an elongated spring member fixed near one end to said chute with its opposite end inclining downwardly opposite said gate, a finger between the ends of said spring member projecting into said passage for engagement with said gate, said finger being of a length to cause said spring member to be flexed away from the passage when the gate is closed, and a blocking finger projecting from said spring member into said passage in a position to deflect coin elements into a particular one of the aforesaid exit passages when the gate is opened, said blocking finger being disposed out of obstructing position by flexing of the spring member when the gate is closed as aforesaid.

2. In a coin chute having a descending coin passage with an entrance opening in its upper region and a plurality of exit openings in its lower region together with a sidewise opening exit and gate therefor disposed between said entrance and exit openings, fraud-preventive means in the form of an elongated strap secured near an end on the outside of said chute so as to incline the opposite end downwardly, said strap thereby being arranged to move in a direction laterally of the chute passage toward and away

from said gate and having a portion disposed substantially opposite the gate, a finger projecting from said strap in unobstructing position across said coin passage for engagement with the inner side of said gate and being of a length sufficient to cause movement of the strap away from the gate out of a normal position when the gate is closed, and a blocking finger on said strap and projecting into blocking position in said passage when the strap is in normal position, said blocking finger being disposed out of blocking relation to the passage when the strap is out of normal position corresponding to closed condition of the gate as aforesaid, said strap being arranged and constructed to move into normal position responsive to opening movement of the gate.

3. In a coin chute of the type including a side exit and a side opening gate therefor, a blocking device cooperable with said gate and including an elongated spring arm fixed at one end on the outside of the chute so that the opposite end may flex toward and away from the gate laterally of the coin passage, a blocking member arranged on said arm for movement by the latter into blocking position relative to said passage when the arm moves into a normal position in a direction toward said gate, said arm being biased for movement into said normal position, and pin means on said arm projecting in a direction laterally of said passage into engagement with said gate and being effective to flex the arm out of normal position by engagement with the gate when the latter is closed, whereby said blocking member will be disposed out of blocking position.

4. A coin chute having, in combination, means providing a descending coin passage with an entrance in its upper region and a plurality of exits in its lower region, a railway beneath said entrance and terminating above said exits, a sidewise exit in the region near the terminus of said railway, a normally closed gate movable laterally away from said passage to open said sidewise exit, coin testing and selecting means for effecting selective movement of coin elements from said railway into said first-mentioned exits, and fraud-preventive means including an elongated arm fixed at one end on the outside of said chute so as to incline the free end portion thereof downwardly in the general direction of said first-mentioned exits, a finger projecting from said arm across said coin passage in unobstructing position so as to be engaged by the inner side of said gate when the latter is closed, said finger being of a length to cause said arm to be moved out of a normal position in a direction away from said gate as a result of engagement of the finger with the gate in the manner aforesaid, and a blocking finger projecting from said arm in a direction across said passage and positioned in blocking position relative to the passage in the region below the terminus of the railway and above said first-mentioned exits when said arm is permitted to move into normal position responsive to opening movement of the gate, whereby to deflect coin elements away from a particular one of said first-mentioned exits, said arm being biased for movement into normal position when the gate is moved away from said first-mentioned finger.

5. In a coin chute of the type including opposite vertical wall members defining a descending coin passage having a plurality of coin exits in its lower region, a discharge exit above said

first-mentioned exits in one of said side wall members, and a gate normally closing said discharge exit and movable into and out of open and closed position laterally of said wall members, fraud-preventive means including an elongated spring blade having one of its ends attached to the side wall portion of the chute opposite the gate so as to incline an opposite free end portion of the blade toward the lower end of the chute, said blade being biased into normal position toward said gate, a blocking finger projecting from the unattached portions of the blade and movable through an opening in said wall portion to which the blade is attached and into blocking engagement by coin elements moving toward said first-mentioned exits for the purpose of guiding coin elements engaging the same into a certain one of said exits, and means for flexing said blade out of normal position to withdraw said blocking finger from the passage, said means including a gate engaging member secured to the unattached portions of the blade and projecting through the chute for engagement with the inner side of said gate when the latter is closed, the gate in closed position flexing said blade through bearing engagement with said gate engaging member. 25

6. In a coin chute of the type having a coin passage defined between opposite wall members with a discharge opening in one of said members and a gate normally closing said opening and movable laterally of said wall members into and out of closed position, blocking means comprising: a spring blade fixed near one end to the outside of the wall member opposite the gate, said blade having a pin passing through said opposite wall member and of a length adequate to be engaged and displaced by said gate so as to spring the blade in a direction away from the gate when the latter is closed, and a coin blocking finger on said blade and spaced away from said fixed end thereof and the pin and extended so as to project through said opposite wall member into said passage to block coin elements when the gate is moved from closed position responsive to movement of the blade back toward normal position, said blocking finger being withdrawn to non-blocking position when the blade is moved a predetermined amount out of normal position responsive to movement of the gate toward closed position as aforesaid. 10
